UNITED STATES PATENT OFFICE.

CARL C. VENEMAN, OF NEW YORK, N. Y.

BELT BUCKLE.

Application filed November 18, 1926. Serial No. 149,236.

This invention relates to belt fasteners in the nature of buckles and in particular to one of simplified construction.

A particular object of the invention is to provide a belt buckle plate and retaining plate in connection with a belt to be worn about the waist which can be adjusted in a variety of different ways and which can be securely locked in position to prevent slipping of the belt relatively to the buckle.

A still further object of the invention is to provide a simplified construction of belt which will embody a retaining plate to which may be secured the buckle plate covering all of the attachments making up the buckle portion of the belt so that the same will present a neat and ornamental appearance at the front of the waist of the wearer or at any other point where the buckle may be positioned.

To enable others skilled in the art to fully comprehend the underlying features of my invention that they may embody the same in the various modifications in structure and relation contemplated, a drawing depicting a preferred form has been annexed as a part of this disclosure and in such drawing, similar reference characters denote corresponding parts throughout all the views, of which,

Figure 1 is a rear view in elevation of the opposite ends of a belt, one end of which is provided with the retaining plate and the other end of which is provided with the buckle plate.

Figure 2 is a front view in elevation of the buckle plate and retaining plate in their connected position, a portion of the buckle plate being broken away to expose its construction and also show its connection with the retaining plate.

Figure 3 is a view in front elevation of the retaining plate, the hook portion of the buckle plate being shown in connection therewith and the belt being shown in outline.

Figure 4 is longitudinal, central section, taken through the assembled buckle plate and retaining plate showing the position of the hook on the buckle plate in its association with said retaining plate.

Figure 5 is a modified form shown in perspective of my improved retaining plate fastened to the end of a belt made of doubled material.

Figure 6 is a sectional view taken on the line 6—6 of Figure 5.

Figure 7 is a view similar to Figure 5 showing the use of my retaining plate in connection with a belt of single ply, and

Figure 8 is a section taken on the line 8—8 of Figure 7.

Referring to the drawing in detail, 5 indicates one end of a belt and 6 the opposite end thereof, to the latter of which is loosely attached my improved buckle plate 7, which consists of the front ornamented plate member 8, as is usual in buckle plates and provided with the outstanding portion 9, one end of the buckle plate being provided with inturned lip members 10 which are formed integrally with said upstanding portion 9. The lips 10 are arranged to extend in over the body of the belt 6 to retain the same in position in the buckle plates. The end of the belt 6 is provided with a plurality of openings 11 through which extends the hook member 12 which is formed integral with the rear surface of the buckle plate 7, it of course being understood that the end of the belt can be adjusted longitudinally of the buckle plate by passing the hook 12 through any of the openings 11, as desired.

In order to provide the belt with a retaining plate, I have sewn within the overturned end of the belt end 5 the flat plate member 13 which is of such width that it may be conveniently positioned within the overturned end of the belt and is arranged along its median line with punched depressions 14, these depressions being provided by cutting the retaining plate as at 15, and then forcing the metal adjacent the point 15 downwardly to provide not only a guide for the hook end but also to provide an opening at the slot or cut 15 into which the end of the hook projects. This is clearly shown in Figure 4 and I have also shown in connection with the plate 13 at each end thereof, a series of downwardly projecting prongs 16 which pierce but do not pass through the material at the end of the belt 5. It is of course understood that when the belt end is turned over to conceal the retaining plate, it is sewn as at 17 on the rear side of the belt 5. In order that the hook 12 may engage any of the openings 14 in the retaining plate, I have provided the cut-out 18 in the belt end 5, this

cut-out exposing the greatest surface of the retaining plate 13 and allowing the hook 12 to be engaged in any of the openings 14 selectively.

5 It is evident, therefore, that varied adjustments can be obtained by placing the hook in any of the openings 11 and by placing the hook 12 into any of the openings 14 in the retaining plate.

10 While I have shown this retaining plate in connection with a double ended belt, it is to be understood that it can be used in any connection and with any type of belt and to this end I have shown in modified form in Figure 5, a retaining plate 19 provided with suitable depressions 20 and prongs 21 which pass through the belt 22 but are bent between the first ply 23 and second ply 24 thereof, so that the ends of 20 the prongs 22 are hidden between the two plies of the belt.

It is of course evident that the under ply 24, as shown in Figure 6, will act to hide the end of the hook 12 of the buckle plate 25 and will also prevent it from catching in the clothing of the wearer of the belt. This, of course, is the object in Figure 4 in turning the ends of the belt 5 under and sewing it as at 17. As shown in this view, the hook 30 12 can do no damage to the clothing of the wearer and the prongs 16 which are sharpened and extend into the under layer of leather, simply prevent longitudinal movement of the retaining plate 13.

35 It is evident that the prongs 21 as shown in the form disclosed in Figures 5 and 6, will not in any way injure the clothing as they are turned in between the first and second layers of the belt.

40 In Figures 7 and 8, I have shown a still further modified form which contemplates the use of the retaining plate 13 in conjunction with the single ply of belt 25 and in order to allow for the hook passing through 45 the depressions 14 in the retaining plate 13, I have provided an elongated cut-out 26 in the belt 25.

Therefore, it is evident that the cut-out in the belt will more or less shield the hook

12 of the buckle plate and will prevent it 50 from catching in the clothing. It will be seen that the prongs 27 are passed through the belt material and are bent over so as to form no projecting points in which the clothing may be caught and consequently 55 torn.

It is evident, therefore, that I have provided a belt having a buckle plate and retaining plate through the medium of which the belt itself can be varied in length by adjusting the buckle plate relatively to the end of the belt proper and by also adjusting the buckle plate relatively to the retaining plate to obtain the adjustment required.

It is also evident that I have provided a 65 buckle plate and retaining plate of simple construction and one which can be readily placed in position on the ends of the belt and which will securely hold the ends of the belt together so that slipping of the ends 70 of the belt relatively is prevented.

While I have illustrated and described my invention with some degree of particularity, I realize that in practice various alterations therein may be made. I therefore reserve 75 the right and privilege of changing the form of the details of construction or otherwise altering the arrangement of the correlated parts without departing from the 80 spirit of the invention or the scope of the appended claim.

Having thus described my invention, what I claim as new and desire to secure by United States Letters Patent is:—

The combination with a belt having a 85 doubled end, of a flat plate secured between the faces of the belt and having a plurality of openings therein, and a buckle carried on the other end of the belt, a hook on said buckle adapted to enter the openings in the plate selectively to releasably secure the same to the buckle, and the belt beneath said openings constituting a covering for the end of the hook whereby it will not touch the 90 clothing of the wearer.

95 In testimony whereof I affix my signature.

CARL C. VENEMAN. [L. S.]
